UNITED STATES PATENT OFFICE.

HORATIO S. EARLE, OF DETROIT, MICHIGAN.

SAND SCREEN.

Application filed October 6, 1921. Serial No. 505,762.

To all whom it may concern:

Be it known that I, HORATIO S. EARLE, a citizen of the United States, residing at Detroit, county of Wayne, and State of Michigan, have invented certain new and useful Improvements in Sand Screens, and declare the following to be a full, clear, and exact description of the same, such as will enable others skilled in the art to which it pertains to make and use the same, reference being had to the accompanying drawings, which form a part of this specification.

This invention relates to sand and gravel screens, and the object of the invention is to provide a screen that is comparatively inexpensive in character; and further to provide a simple and inexpensive device for spacing the wire strands over which the screen is formed, the spacing means being adapted to securely hold the strands in the desired relative position and being readily removed or attached. A further object of the invention is to provide a construction that prevents longitudinal as well as transverse displacement of the wire strands. Another object of the invention is to provide a sand screen in which the wire strands thereof are corrugated and, when the screen is made up, the grooves and ridges of the corrugations extend transversely of the screen. A still further object of the invention is to provide a screen of the character described in which the corrugations of the strands extend in a plane at a right angle to the plane of the screen, each strand being formed with a depression at spaced intervals by which the strands may be secured in spaced relation in an apertured plate for connecting the same together. These objects and the several novel features of the invention are herein-after more fully described and claimed and the preferred form of construction by which these objects are attained is shown in the accompanying drawings in which—

Fig. 1 is a perspective view of a sand and gravel screen embodying my invention,

Fig. 2 is a plan view of a section of the screen,

Fig. 3 is a bottom view thereof,

Fig. 4 is a view of a portion of the slotted spacing device for securing the strands in spaced relation, and

Fig. 5 is a section taken on line 5—5 of Fig. 2.

In Fig. 1 the usual type of screen is shown consisting of a frame 1 having supporting

legs 2, and the cross members 4 of the screen are secured across the frame 1. These cross members 4 as shown in Fig. 4 are provided with a series of spaced slots 5 for a purpose 60 hereinafter described. The wire strands 8 of the screen as shown in Fig. 5 are provided with depressed portions 6 at spaced intervals throughout their length and the wire strands between the depressed portions 6 are formed 65 with a series of corrugations 7. The depressed portions 6 of the wire strands 8 are inserted through the slots 5 of the plates 4 and a heavy wire or rod 9 is inserted between the depressed portions 6 and the plates 4, as 70 shown in Figs. 2, 3 and 5, which holds the strands in spaced relation, the end of the wires or rods 9 being turned over at 10 at the edge of the screen to secure the parts in place. The wire strands are secured in place 75 with the corrugations thereof in a plane extending at a right angle to the plane of the screen and the grooves and ridges of the corrugations 7 extending across the screen parallel to the plates 4. Thus it can be seen 80 that when sand and gravel is thrown onto the screen shown in Fig. 1 the same will tend to ride downwardly on the wire strands which act as ways for the gravel and the gravel in passing over the corrugations 85 which extend across the screen is vibrated thereby and is jarred upon striking each corrugation so that all of the fine material will pass through the screen much more easily by this shaking action than as though the 90 wire strands were perfectly straight. It will also be noted from Fig. 5 that the plates 4 do not extend upwardly into the ways provided by the wire strands but are positioned beneath the plane of the screen, the object 95 being to so position the plates 4 that the gravel does not strike the same when passing over the screen, and in this manner clogging of the screen is prevented. For this reason the wire strands are provided with high 100 points 11 at each side of the depressions 6 so that the gravel on the strands cannot become lodged against the edge of the plates but may strike the plates in the central portion between the high points 11 which aid in 105 shaking the gravel. While I have shown a flat screen it is to be understood that cylindrical screens of other types may be made in which this construction is utilized.

From the foregoing description, it becomes 110 evident that the device is very simple and efficient in operation, is easily put together

or taken apart, will not get out of order or clog, and provides a device which accomplishes the desired result.

Having thus fully described my invention, 5 its utility and mode of operation, what I claim and desire to secure by Letters Patent of the United States is—

1. A screen fabric consisting of a series of parallel wire strands corrugated in a plane 10 at a right angle to the plane of the screen and provided with U-shaped depressions in spaced intervals, a series of spacing devices 15 consisting of a flat plate having slots through which the U-shaped depressions of the strands extend, a fastening wire extending through the U-shaped depressions beneath each spacing device and having an end bent about one of the said U-shaped portions.

2. A screen fabric consisting of a series of 20 parallel wires each provided with U-shaped depressions at spaced intervals and intervening corrugations, a series of spacing devices secured to the depressions beneath the plane of the screen, the grooves and ridges of the 25 corrugations of the different strands extending in alignment transversely of the screen and parallel to the spacing devices.

3. A screen fabric consisting of a series of 30 parallel wire strands corrugated in a plane at a right angle to the plane of the screen and provided with U-shaped depressions at spaced intervals and a series of spacing devices secured to the U-shaped depressions beneath the plane of the screen. 35

In testimony whereof, I sign this specification.

HORATIO S. EARLE.
